UNITED STATES PATENT OFFICE.

HENRY HORNE, OF NEW BRITAIN, CONNECTICUT, ASSIGNOR TO THE CORBIN CABINET LOCK COMPANY, OF SAME PLACE.

DESIGN FOR A PADLOCK-CASE.

SPECIFICATION forming part of Design No. 22,456, dated May 23, 1893.

Application filed March 11, 1893. Serial No. 465,647. Term of patent 14 years.

To all whom it may concern:

Be it known that I, HENRY HORNE, a citizen of the United States, residing at New Britain, in the county of Hartford and State of Connecticut, have invented and produced a new and original Design for Padlock-Cases, of which the following is a specification, reference being had to the accompanying drawings, in which—

- 10 Figure 1 is a side elevation of a padlock case showing my design. Fig. 2 is a side elevation of the reverse side of the same, and Fig. 3 is an edge view.

My padlock case is circular in side view and somewhat in the form of a thickened disk in edge view with slightly rounded corners as shown in Fig. 3. Upon each side thereof is a central circle or circular site 4, immediately outside of which is a circular band 5 upon

which I propose to place any desired lettering, as for instance the name of the maker. Surrounding said band 5 is a milled or transversely marked bead 6, outside of which the case is plain and continuous to the edge. Upon one side, within the site or circle 4, is the head of Columbus as shown in Fig. 1, and upon the reverse side is an illustration of one of his ships as shown in Fig. 2, the said illustrations of the head and ship being on a slightly roughened or stippled ground. 20 25 30

What I claim is—

The design for a padlock case as herein shown and described.

HENRY HORNE.
